UNITED STATES PATENT OFFICE.

HERBERT H. HEWITT, OF BUFFALO, NEW YORK.

CAR-TRUCK.

1,009,747.

Specification of Letters Patent. Patented Nov. 28, 1911.

Application filed March 7, 1910. Serial No. 547,361.

To all whom it may concern:

Be it known that I, HERBERT H. HEWITT, a citizen of the United States, residing at Buffalo, county of Erie, State of New York, have invented certain new and useful Improvements in Car-Trucks, of which I do declare the following to be a full, clear, and exact description, reference being had to the accompanying drawings, forming part 10 of this specification.

Figure 1 is a plan view of a car truck embodying my invention. Fig. 2 is a view in side elevation. Fig. 3 is a view in central vertical section on the line 2—2 of Fig. 1, the bolster being shown in elevation. Fig. 4 is a view in horizontal section on the line 4—4 of Fig. 2, one of the journal boxes being shown in elevation. Fig. 5 is a detail view in central vertical section through the 20 central portion of one of the side frames with the end of the transom therein, the locking devices being shown in elevation. Fig. 6 is a view in cross section on the line 6—6 of Fig. 4.

The present invention has for one of its objects to provide an improved construction of truck for railway cars in which the side frames of the truck shall be secured to the transverse member or transom 25 in such manner as to permit an independent vertical, rotary or pivotal movement of the side frames with respect to the transom and in such manner also as to provide for a pivotal movement of the journal boxes 30 with respect to the side frames wherein they are mounted, so that the strains upon the truck frame and the parts thereof incident to depressions or irregularity of the tracks and inequalities of wear upon the bearings 35 will be avoided and an easier riding action of the trucks will be insured.

The invention consists in the various novel features of improvement hereinafter described, illustrated in the accompanying 45 drawings and particularly pointed out in the claims at the end of this specification. I wish it distinctly understood, however, that while I have described in this specification, what I regard as the preferred embodiment of my invention, the details of the invention may be varied within wide limits without departure from the scope of the invention, and features of the invention may be employed without its adoption as an entirety.

In the drawings A, A designate the side

frames of my improved truck. These side frames may be made either of cast or wrought metal, so shaped as to provide central openings to pivotally receive the ends 50 of the truck transom and with end openings wherein will be pivotally sustained the journal boxes.

B designates my improved construction of transom that may be formed either of 55 cast or wrought metal. The main portion of the transom B consists of channel-shaped side portions b that are integral with or suitably united to the end portions b'. The extreme ends b² of the transom B are of 60 cylindrical shape and are somewhat smaller than the adjacent end portions b'. Each end portion b² of the transom B will have its exterior surface machined so as to accurately fit within the opening a of the corresponding side frame A. The central portion of the side frame A is flanged as at a' about its cylindrical opening a and, as will be seen more particularly by reference to Figs. 4 and 5, pockets or seats a² are formed 65 at opposite points in the wall of the opening a of each of the side frames A. Through each of the cylindrical chambered ends of the transom B are formed slots or openings b⁵ through which will project the bolts C 70 that serve as the preferred means for locking the transom B to the side frames A. By reference more particularly to Fig. 5 of the drawings, it will be seen that each of the slots b⁵ are slightly longer than the vertical 75 dimension of the bolts C, so as to permit a rocking movement of the side frames in vertical direction with respect to the transom, while limiting the extent of this rocking movement. From each of the bolts C 80 extends inwardly a threaded rod c that is engaged by a turn-buckle C' and by means of this turn-buckle the bolts can be withdrawn from the seats or pockets a², when it is required to disconnect the side frames A 85 from the transom B. The cylindrical ends of the transom B fit snugly, yet pivotally, within the openings a of the side frames and are effectively held against longitudinal movement by the locking bolts C. It will be 90 readily seen that when the side frames are to be removed from the transom B, the bolts C can be withdrawn by actuating the turn-buckles until the ends of the bolts pass out from the pockets or seats a², but when the 95 parts are in the positions shown in the several views of the drawings, the side frames

will be securely united to the transom in such manner as to have, individually, a pivotal or rocking movement with respect thereto.

5 By reference more particularly to Fig. 2 of the drawings it will be seen that the side frames have the openings so disposed therein that these frames are reversible and, hence, if any excessive wear occurs, for 10 example, at the upper portion of the central opening a , the side frame can be readily removed and reversed so that the part which before was the top of the side frame will become the bottom; and this reversibility 15 of the side frames is further advantageous because it avoids all danger of any mistake in the proper attachment of the side frames in position, as the side frames can be used upon either side of the truck.

20 The main portion of the transom B is chambered or open to a sufficient extent to admit the bolster D and to receive the springs E and the spring seats or blocks F whereon these springs are mounted. The 25 spring blocks F are shown as supported by the stirrups or straps G which are U-shaped and set between the side walls b of the transom B and have their upper ends turned outwardly and secured to the top of the side 30 walls or bars b , as shown in Fig. 1. The bolster D may be of any suitable or approved construction and will be furnished upon its upper surface with suitable side and center bearing blocks, as well understood by those familiar with this class of 35 devices.

Adjacent their ends the side frames A are formed with flanges a^4 within which are the openings to receive the journal boxes H and the retaining rings or keepers K , whereby these journal boxes are held in engagement with the side frames. The journal boxes H are fitted interiorly with suitable 40 bearings for the journals m of the axles M , but the details of these journal boxes need not be more fully described, as such boxes will be included in a separate application 45 for Letters Patent. In the preferred embodiment of my invention each of the journal boxes H is of a general spherical shape and each journal box is retained within its appropriate opening at the end of the side frame by means of the retaining rings or 50 keepers K . The keepers K are preferably 55 formed of two rings, each of which has its exterior surface screw threaded to engage the correspondingly threaded opening at the end of the side frame and each of these rings is preferably formed with a flange or 60 shoulder k at its outer end. The interior surfaces of the two rings K which engage the same journal box H , are reversely 65 curved, so that when the rings are in position for use, as shown in the drawings, they will accurately fit the spherical surface of

the journal box and securely hold it in engagement with the side frame, while at the same time permitting a swivel or universal movement of the journal box with respect to the side frame. The outer end of each of the retaining rings K is preferably formed with a series of holes k^2 adapted to receive a spanner wrench to permit the rings to be readily screwed to place or withdrawn.

70 It will be understood that while I prefer to form the two rings K removable from the side frame A , it is necessary that but one of said rings be removable, as it will be obvious that the other half of the seat formed thereby may be formed integral with 80 the side frame A without interfering with the removal of the spherical journal box H therefrom when desired.

85 From the foregoing description it will be seen that when the side frames A have been placed upon the cylindrical ends of the bolster B the locking bolts C will securely retain the side frames in position, with the inner faces of the side frames abutting against the shoulder b^4 of the end portion 90 b^7 of the bolster. When it is desired to make repairs, as for example, to replace a worn or defective wheel, it is simply necessary to jack up the transom D , withdraw the locking bolts C , C from the pockets a^3 and slip 95 off the side frames, without removing the journal boxes therefrom. When the wheels are replaced the side frames can then be slipped back on to the end portions of the bolster and secured in place as before.

100

It will be seen that inasmuch as the side frames are pivotally connected to the ends of the transom or transverse member that unites them and are connected also with the journals of the car axle by a swivel or 105 universal joint, any obstruction or depression in the track that may lift or depress a wheel will cause the adjacent side frame to rock about the end of the transom in a vertical longitudinal plane and will cause the 110 axle of the wheel so lifted or depressed to yield pivotally at approximately right angles to the plane of the side frame. When a wheel is thus lifted or depressed and the corresponding end of the axle is thus raised 115 or lowered, the axle also has a slight movement toward the transverse center of the truck which would tend to cramp and strain the parts, except for the pivotal movement allowed by the journal box. The result is 120 that the strains and shocks incident to the lifting and depression of the wheels under irregularity of the track are very greatly relieved. It is obvious also that even where the side frames are not pivotally connected, 125 there may be such flexibility between these frames that the employment of the spherical boxes and keepers will prove most advantageous. Moreover, the pivotal movement of the journal box will insure that at all 130

times a true alinement of the bearing with the journal shall be maintained, so that the danger of excess wear or strain upon the bearing at any point is avoided.

5 Having thus described my invention what I claim as new and desire to secure by Letters Patent, is:—

1. A car truck comprising side frames, a transverse member pivotally connected at 10 its ends to said side frames, and wheel axles having their ends pivotally engaged with said side frames in manner permitting said axles to rock in planes substantially transverse to the plane of the side frames.

15 2. A car truck comprising side frames, a transom having its ends journaled in said side frames, wheel axles, and journal boxes for said axles swiveled in said side frames to rock in planes substantially transverse 20 thereto.

25 3. A car truck comprising side frames, a transom having its ends journaled in said side frames, wheel axles and journal boxes for said axles, said axles being connected by universal joints with said side frames.

30 4. A car truck comprising side frames having central openings therein, a transom having cylindrical ends journaled in said openings and means movable transversely 35 to said transom for securing said side frames against longitudinal movement on said transom.

35 5. A car truck comprising side frames having central openings therein, a transom 40 having its ends journaled in said openings, and parts extending transversely through said transom ends and interlocking with said side frames to limit the rocking movement of said side frames upon said transom ends.

45 6. A car truck comprising connected side frames, each of said side frames being similarly shaped at its top and bottom and consisting of a single, integral metal part having a central web and an edge flange, said web having circular openings at its ends and at its center with flanges surrounding said openings, said central and end openings being in substantially longitudinal alinement.

50 7. A car truck comprising side frames having central openings therein, a transom having chambered ends journaled within the openings of the side frames and means passing through the end walls of said transom and engaging said side frames to hold said side frames against longitudinal displacement.

55 8. A car truck comprising side frames having central openings therein, a transom having chambered ends journaled within the openings of the side frames and means located within the chambered ends of the transom for uniting the side frames to the transom.

60 9. A car truck comprising side frames

having cylindrical openings therein, a transom having cylindrical ends journaled in said openings and having a body portion chambered to receive the bolster, springs or other parts.

70 10. A car truck comprising side frames, a transom having its ends journaled in said side frames, the body of said transom being formed integral with said ends and being chambered to receive the bolster, springs or other parts. 75

75 11. A car truck comprising side frames, a transom having its ends journaled in said side frames, and locking bolts extending at right angles to said transom and holding the ends thereof within said side frames. 80

80 12. A car truck comprising side frames, a transom having cylindrical ends journaled in said side frames and locking bolts extending through the cylindrical ends of the transom and engaging the side frames to hold said side frames upon said transom. 85

85 13. A car truck comprising side frames, a transom having cylindrical ends journaled in said side frames, one of said parts being formed with pockets and the other with slots, and bolts for holding said side frames upon the ends of said transom and arranged to enter said pockets and slots. 90

90 14. A car truck comprising side frames having central openings, the walls of which are provided with seats or pockets, a transom having cylindrical ends journaled in said side frames, and locking bolts passing through said transom ends and into the seats or pockets in the side frames for holding the side frames upon the ends of the transom. 95

95 15. A car truck comprising side frames, a transom having cylindrical ends journaled in said side frames, locking bolts for holding said side frames in position upon said transom ends and a turn-buckle for operating said locking bolts. 105

100 16. A transom for car trucks comprising a body that is chambered to receive the bolster, springs or other parts and the ends whereof are formed of cylindrical outline whereby they may be journaled in the side frames of the truck. 110

110 17. A transom for car trucks comprising a body formed of parallel side members and cylindrical ends adapted to be journaled in the side frames of the truck, said transom body being open between said side members and said ends to receive the bolster, springs or other parts. 120

120 18. A car truck comprising side frames having integral, central bearing portions, a transom having chambered cylindrical end portions journaled in said side frames, said transom having shoulders at the inner ends of said cylindrical portions against which said side frames abut, and adjustable bolts arranged within said chambered cylindrical 125 portions. 130

portions and extending through seats therein and in said side frames for holding said side frames upon the ends of said transom.

19. A transom for car trucks comprising a chambered body adapted to receive the bolster, springs or other parts and having chambered cylindrical ends adapted to be journaled within the side frames of the truck.

20. A side frame for car trucks having a web-like body provided with a marginal flange and having circular central and end openings, said openings being provided with flanges completely surrounding the same.

21. A reversible side frame for car trucks having a web-like body and having circular central and end openings in substantially horizontal alignment, each of said openings being provided with a flange completely surrounding the same, said side frame having a continuous marginal flange and similarly shaped upper and lower portions.

22. A reversible side frame for car trucks having a central opening adapted to receive the journal end of a transom, the upper and lower portions of said side frames being similarly shaped.

23. A side frame for car trucks having openings formed through its ends to receive the car axle journals, said openings being screw threaded.

24. A car truck comprising side frames, a transverse member pivotally connected at its ends to said side frames, wheel axles, journal boxes for said axles, said journal boxes having spherical body portions correspondingly shaped retaining members mounted upon the ends of said side frames, said journal boxes being movably mounted within said retaining members.

25. A car truck comprising side frames, a transom connecting said side frames and having its ends journaled therein, spherical journal boxes movably mounted in correspondingly shaped seats in the ends of said side frames, and wheel axles mounted in said journal boxes.

26. A car truck comprising side frames having central openings therein, a transom having its ends pivotally engaging said openings to permit the rocking movement of said side frames, said transom having a chambered body adapted to receive the bolster and its supporting springs, wheel axles, and journal boxes for said axles secured against relative vertical movement upon the ends of said side frames.

27. A car truck comprising side frames having central openings therein, a transom having its ends pivotally engaging said openings, wheel axles having projecting journals at their ends, boxes for receiving said journals mounted upon the ends of said side frames, locking bolts extending transversely through said transom ends and engaging said side frame for removably hold-

ing the latter in position upon the ends of said transom and said axle journals, said bolts being arranged to permit the rocking movement of said side frames.

28. A car truck comprising side frames, a transom pivotally connected at its ends to the central portions of said side frames to permit the rocking movement of the latter, a bolster and its supporting springs carried by said transom, wheel axles, and journal boxes for said axles having spherical body portions movably mounted within concave spherical seats at the ends of said side frames and held against relative vertical movement in said seats.

29. A car truck comprising flexibly connected side frames, wheel axles, journal boxes for said axles having spherical body portions movably mounted within correspondingly shaped, concave seats at the ends of said side frames, and keepers for said journal boxes removably secured to the ends of said side frames, said concave, seats being formed, at least in part, in said keepers.

30. A car truck comprising side frames, a transom engaging the central portions of said side frames and flexibly connecting the same, a bolster and its supporting springs carried by said transom, wheel axles having projecting journals at their ends, boxes for receiving said journals having continuous, annular, spherical body portions movably mounted within correspondingly shaped, concave seats at the ends of said side frames, and keepers for holding said journal boxes in position rigidly but removably secured to the ends of said side frames, said spherical concave seats being formed, at least in part, in said keepers.

31. A car truck comprising flexibly connected side frames having openings in their ends, wheel axles having projecting journals at their ends, boxes for said journals arranged within the end openings in said side frames, said boxes having continuous, annular, spherical body portions, and annular keepers removably secured in position within the end openings of said side frames and having concave spherical seats wherein said journal boxes are movably mounted.

32. A car truck comprising side frames, a transom pivotally connected to the central portions of said side frames to permit the rocking movement of the latter, a bolster and its supporting springs carried by said transom, wheel axles having projecting journals at their ends, boxes for said journals having spherical body portions movably mounted within correspondingly shaped seats in the ends of said side frames, keepers for holding said journal boxes in position rigidly but removably secured to said side frames, said spherical, concave seats being formed, at least in part, in said keepers.

33. A car truck comprising side frames, a

transverse member flexibly connecting the central portions of said side frames, bearing boxes having annular, spherical body portions movably mounted within correspondingly shaped, concave seats at the ends of said side frames, said boxes being held in said seats against vertical movement relative to said side frame ends, and wheel axles having projecting end journals rotatable within said bearing boxes.

34. A car truck comprising side frames having central openings therein, a transom having its ends journaled in said openings, said transom having a chambered body 15 adapted to receive a bolster and its supporting springs, wheel axles having projecting journals at their ends, bearing boxes wherein said journals are rotatable, said boxes being secured against relative vertical movement upon the ends of said side frames, and locking bolts engaging said transom ends and said side frames for removably holding the latter in position upon said axle journals and upon the ends of said transom while 25 permitting the rocking movement of said side frames.

35. A car truck comprising centrally connected side frames having internally screw

threaded openings at their ends, journal boxes having annular, spherical body portions arranged within said openings, annular flanged keepers threaded within said openings, said keepers having concave spherical seats wherein said journal boxes are movably mounted, and wheel axles having projecting end journals rotatable within said journal boxes.

36. A car truck comprising centrally connected side frames, bearing boxes having annular, spherical body portions, movably mounted within correspondingly shaped concave seats at the ends of said side frame, the spherical surfaces of said journal boxes and of said seats being in direct engagement, keepers for holding said journal boxes in position rigidly but removably secured to said side frames, said spherical concave seats being formed, at least in part, in said keepers, and wheel axles having projecting end journals extending within and rotatably engaging said bearing boxes.
